(57) **CLAIM**

The ornamental design for a table lamp, as shown and described.

DESCRIPTION

FIG. 1 is a front perspective view of a table lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the table lamp shown in use;

FIG. 10 is a perspective view of the table lamp shown in use;

FIG. 11 is a perspective view of the table lamp shown in use;

FIG. 12 is a perspective view of the table lamp shown in use;

FIG. 13 is a perspective view of the table lamp shown in use;

FIG. 14 is a perspective view of the table lamp shown in use;

FIG. 15 is an enlarged detail view of area 15 in FIG. 1;

FIG. 16 is an enlarged detail view of area 16 in FIG. 1;

FIG. 17 is an enlarged detail view of area 17 in FIG. 1;

FIG. 18 is an enlarged detail view of area 18 in FIG. 1;

FIG. 19 is an enlarged detail view of area 19 in FIG. 2; and,

FIG. 20 is an enlarged detail view of area 20 in FIG. 2.

The broken lines in the drawings illustrate the portions of the Table Lamp, which form no part of the claimed design.

The dash-dot-dash broken lines in FIGS. 1, 2, and 15-20 delineate areas of the figures shown enlarged and form no part of the claimed design.

1 Claim, 20 Drawing Sheets
